UNITED STATES PATENT OFFICE.

ELIAS WIRTH-FREY, OF AARAN, SWITZERLAND, ASSIGNOR TO SULZER FRÈRES SOCIÉTÉ ANONYME, OF WINTERTHUR, SWITZERLAND, A CORPORATION OF SWITZERLAND.

ABSORPTION REFRIGERATING MACHINE.

Application filed March 14, 1924, Serial No. 699,159, and in Germany April 19, 1923.

This invention relates to an absorption refrigerating machine comprising a generator-absorber, an evaporator and a condenser, and has for its primary object to prevent overfilling the evaporator and filling up the condenser with liquid and also to avoid the possibility of the generator being emptied and the heater going dry. Further objects of the invention are to prevent solution from 5 being forced back out of the generator-absorber through the suction or absorption pipe into the evaporator, during the expulsion period, and to prevent a back-flow of refrigerant from the evaporator through the 10 pressure or expulsion pipe into the generator-absorber after the heat is cut off and during the absorption period.

In the absorption refrigerating machine according to the present invention the condenser and the evaporator are both disposed at a higher level than the generator-absorber, the condenser is further arranged above the evaporator, there is further provided a pressure or expulsion pipe connecting 15 the generator-absorber and the condenser, connecting means between the condenser and the evaporator, a suction or absorption pipe connecting the evaporator and the generator-absorber, and a by-pass passage between 20 the evaporator and the generator-absorber.

The pressure pipe is conveniently provided with a resistance, which may be produced by providing this pipe with a liquid seal or by 25 leading the pipe up to a sufficient height above the condenser or by both means simultaneously. The resistance in the pressure pipe is preferably divided up into a number of partial resistances. Thus one or more receivers may be provided in the pressure pipe to contain liquid trapped therein, consecutive 30 receivers being connected together by by-pass passages each containing a liquid seal, whilst a further by-pass passage is preferably provided to connect one of the end receivers with the evaporator or the suction line. An enlargement may be provided at the upper end 35 of the portion of the pressure pipe containing a liquid seal.

50 The absorption or suction pipe may also be provided with an automatically operating resistance device, either by utilizing the hydrostatic pressure resulting from a suitably chosen difference in level between the

evaporator and the generator absorber, or by 55 leading the suction pipe up to a sufficient height above the evaporator. The by-pass passage being in the form of a liquid seal preferably opens into the gas-filled space in the generator-absorber.

60 The accompanying drawings illustrate in Figures 1-3 by way of example some constructions according to the invention.

The known constructions are open to objection in that it is necessary to provide external mechanical means whereby the liquid residues collecting in the evaporator can be discharged therefrom. Moreover these constructions are not provided with safety devices which come into operation if the cooling devices fail to act or which operate to prevent a complete evaporation of the whole contents of the generator-absorber, so that with electric heating it is possible for example for the heating element to burn out. 75 These known machines have a further disadvantage when the suction pipe is separate from the pressure pipe in that when operating automatically solution may be forced out of the generator-absorber through the suction pipe into the evaporator during the expulsion period, or a back-flow through the pressure pipe may occur after the heat is cut off and during the absorption period.

70 With the machine according to the present invention on the other hand, overfilling the evaporator and filling up the condenser with liquid is rendered impossible by the setting up of a liquid circulation. Again should disturbances of any kind occur in working, 80 such for example as when the cooling devices fail to act or when the heat is not cut off, a liquid circulation is set up and the heater is prevented from going dry. Moreover the construction of the suction and pressure pipes 85 may be such as to prevent solution from being forced into the evaporator during the expulsion period, or refrigerant from being allowed to flow back through the pressure pipe 90 during cooling.

95 In all the constructions illustrated in the figures the refrigerating machine comprises a generator-absorber 1, a condenser 2 and an evaporator 3, the two latter being disposed at a higher level than the generator-absorber. The gases expelled from solution by heating 100 the generator-absorber 1 pass through the pressure pipe 4 into the condenser 2 where

they are liquefied in the known manner by the action of a cooling medium. The pressure pipe 4 may be valve controlled, if desired. From the condenser 2, in front of which may be provided a water separator not shown, the liquid refrigerant passes either directly or past a controlling valve through a pipe 6 into the evaporator 3, where the refrigeration action takes place by withdrawing from the surroundings the heat necessary for vaporizing the refrigerant. When the heat is cut off from the generator-absorber 1 and cooling devices therein are brought into action, the vaporized refrigerant is absorbed through the suction pipe 7 in consequence of the reduced pressure resulting from the cooling action. The evaporator 3 is in communication through a by-pass passage 8 with the generator-absorber 1, so that any excess of liquid refrigerant or solvent, which tends to overfill the evaporator, can flow back into the generator-absorber.

In order to prevent solution from being forced from the generator-absorber 1 into the evaporator 3 during the expulsion period, the suction pipe 7 is provided with a resistance device which produces a resistance which in order to be effective, must be greater than the total resistance in the pressure pipe 4 taken up to the junction of the two pipes in front of or at the evaporator.

In Figures 2 and 3 the by-pass passage 8 leads from the evaporator 3 into the suction pipe 7.

In the figures the resistance in the suction pipe 7 is produced by leading this pipe up to a sufficient height above the evaporator. In Figure 1 the by-pass passage 8 contains a liquid seal and leads into the gas-filled part of the generator-absorber 1. The resistance in the suction pipe may also be produced by utilizing the hydrostatic pressure resulting from a suitably chosen difference in level between the evaporator 3 and the generator-absorber 1.

The figures show constructions in which the pressure pipe 4 is provided with a resistance device, for the purpose of preventing back flow of refrigerant from the evaporator or the condenser through the pressure pipe into the generator-absorber after the supply of heat to the generator is cut off and during absorption.

In the Figures 1 and 2 this resistance is produced by leading the pressure pipe 4 to a height above the condenser 2. This pipe contains a liquid seal formed by the pipe 9, which is provided at its upper end with an enlargement 10 and is connected at its lower end to a receiver 11. The receiver 11 is connected to the suction pipe 7 through a by-pass passage 12. The arrangement of the suction pipe 7 in this construction is the same as that shown in Figure 1 with the exception that the by-pass passage 8 opens into the suction pipe. When gas starts to flow back along the

pressure pipe 4 towards the generator-absorber, the liquid in the receiver 11 is forced up into the tube 9, which acts as a liquid seal and prevents the back flow of the gas. The receiver 11 always remains full of liquid since it is supplied with fresh liquid during each expulsion period up to the level of the by-pass passage 12.

In Figure 3 the resistance in the pressure pipe 4 is divided up into a number of partial resistances arranged in series. Each partial resistance is produced by means of a pipe 9 which has an enlargement 10 at its upper end and is connected at its lower end to a receiver 11, consecutive receivers being connected together by means of by-pass passages 12 each formed to contain a liquid seal. The last receiver 13 is connected through a by-pass passage 14 directly to the evaporator 3, so that the liquefied refrigerant does not miss its evaporation. The receivers 11 or the pipes 9 may be provided with non-return valves, if desired, in order still further to increase the safety factor. The arrangement illustrated in Figure 3 has the advantages that the height of the machine can be reduced and that greater security of operation is ensured, since any irregularities in working are more effectively damped out by the numerous enlargements than would be possible with the arrangement shown in Figure 2.

It will be understood that the invention is not limited to the arrangements illustrated and that modifications may be made without departing from the scope of the invention.

I claim:

1. In an absorption refrigerating machine, the combination with a generator-absorber of an evaporator disposed at a higher level than the generator-absorber, a condenser arranged above the evaporator, an expulsion or pressure pipe connecting the generator-absorber and the condenser, connecting means between the condenser and the evaporator, a suction or absorption pipe connecting the evaporator and the generator-absorber, the said pressure pipe branching separately from the said suction pipe, and an unobstructed continuously open overflow device between the said evaporator and the said generator-absorber.

2. In an absorption refrigerating machine, the combination with a generator-absorber of an evaporator disposed at a higher level than the generator-absorber, a condenser arranged above the evaporator, an expulsion or pressure pipe connecting the generator-absorber and the condenser, connecting means between the condenser and the evaporator, a suction or absorption pipe connecting the evaporator and the generator-absorber, the said pressure pipe branching separately from the said suction pipe, and an unobstructed continuously open overflow device which connects the lowest part of the evaporator and the generator absorber.

3. In an absorption refrigerating machine, the combination with a generator-absorber of an evaporator disposed at a higher level than the generator-absorber, a condenser arranged 5 above the evaporator, an expulsion or pressure pipe connecting the generator-absorber and the condenser, connecting means between the condenser and the evaporator, a suction or absorption pipe connecting the evaporator 10 and the generator-absorber, the said pressure pipe branching separately from the said suction pipe, and a by-pass passage between the said evaporator and the said generator-absorber, and means including a liquid seal in 15 said expulsion pipe for forming an automatically operating resistance to the flow of fluid therethrough.
4. In an absorption refrigerating machine the combination with a generator-absorber of 20 an evaporator disposed at a higher level than the generator-absorber, a condenser arranged above the evaporator, an expulsion or pressure pipe connecting the generator-absorber and the condenser, connecting means 25 between the condenser and the evaporator, a suction or absorption pipe connecting the evaporator and the generator-absorber, the said pressure pipe branching separately from the said suction pipe, and an unob- 30 structed continuously open overflow device between the said evaporator and the said generator-absorber, an enlargement in said 35 expulsion pipe, a receiver connected with said enlargement containing a liquid forming a column between said enlargement and receiver, thus forming means to seal the expulsion pipe during the absorption period and to direct the flow of gas through the absorption pipe into the generator-absorber.
5. In an absorption refrigerating machine the combination with a generator-absorber of an evaporator disposed at a higher level than the generator-absorber, a condenser arranged above the evaporator, an expulsion 45 or pressure pipe connecting the generator-absorber and the condenser, connecting means between the condenser and the evaporator, a suction or absorption pipe connecting the evaporator and the generator-absorber, the 50 said pressure pipe branching separately from the said suction pipe, an unobstructed continuously open overflow device between the said evaporator and the said generator-absorber, an enlargement in said 55 expulsion pipe, a receiver connected with said enlargement containing a liquid forming a column between said enlargement and receiver, and a further by-pass passage connecting the receiver to the suction pipe.
6. In an absorption refrigerating machine, 60 the combination with a generator-absorber of an evaporator disposed at a higher level than the generator-absorber, a condenser arranged above the evaporator, an expulsion or pressure pipe connecting the generator-absorber 65 and the condenser, connecting means between the condenser and the evaporator, a suction or absorption pipe connecting the evaporator and the generator-absorber and an unob- 70 structed continuously open overflow device between the evaporator and the generator-absorber, said absorption pipe being shaped to utilize the hydrostatic pressure resulting from a suitable difference in level between the evaporator and the generator-absorber 75 for forming an automatically operating resistance to the flow of fluid through said pipe.
7. In an absorption refrigerating machine, the combination with a generator-absorber of an evaporator disposed at a higher level 80 than the generator-absorber, a condenser arranged above the evaporator, an unobstructed continuously open overflow device between the evaporator and the generator-absorber, an expulsion or pressure pipe connecting the 85 generator-absorber and the condenser, connecting means between the condenser and the evaporator, a suction or absorption pipe connecting the evaporator and the generator-absorber an enlargement in said 90 expulsion pipe, a receiver connected with said enlargement and containing a liquid adapted to vary its level and to form a column between said enlargement and receiver and means to allow the liquid to flow back from the receiver 95 through the suction pipe into the generator-absorber.

In testimony whereof I have affixed my signature.

ELIAS WIRTH-FREY.
